EMORY J. LIPPS, OF FOUNTAIN HILL BOROUGH, PENNSYLVANIA.

WINDING MECHANISM.

1,103,676.

Specification of Letters Patent. Patented July 14, 1914.

Application filed February 16, 1914. Serial No. 818,841.

To all whom it may concern:

Be it known that I, EMORY J. LIPPS, a citizen of the United States, residing at borough of Fountain Hill, in the county 5 of Lehigh and State of Pennsylvania, have invented certain new and useful Improvements in Winding Mechanisms, of which the following is a specification.

This invention relates to wound package-forming mechanism of the general class in which one of the two members affording an axial support for the package and a guide for the thread or yarn rotates around the axis of the supporting member to accomplish the winding, one reciprocates longitudinally of said axis to lay the windings spirally around said axis, and one is shifted longitudinally of said axis, due to impact of the thread-guide member at intervals with the package, to advance the point of winding from time to time, so that the windings come to be disposed in the finished package generally as conical layers. Where such packages are wound on wooden or similar quills, means is afforded by the enlargement at the quill butt for supporting the windings at the butt of the package; but where they are formed on paper or similar tubes having no enlargement at the butt to support the windings means have to be provided in the winding machine for so controlling the winding of the butt of the package as to make the same as well as its point or free end tapered, thereby to prevent its coils at the butt loosening and falling away in handling. Such means have heretofore been more or less complicated and cumbersome; and it is therefore the object of this invention to simplify the same. I accomplish this object, briefly stated, by providing the support around which the windings are coiled and in the portion thereof surrounded by the butt-coils of the package with a lateral offset, formed usually to converge forwardly toward the axis of winding. In the adaptations herein shown and described this offset serves to displace laterally, or to maintain laterally displaced, a part of the butt of the cop-tube as a lateral offset thereof when the tube is forced on the spindle; but it should be understood that the invention is not limited to the offset having this supplemental function, the essential feature being a lateral offset on the support around which the windings are formed and in the

part thereof surrounded by the butt-windings, whereby means is afforded by which, without complicated mechanism, the building of the heel or butt of a cop or other 60 wound package can be started without the instrumentality of the conical enlargement characteristic of a quill.

In the accompanying drawings, Figure 1 shows the essential elements of a quilling machine, which is chosen as illustrative of the class of winding machines above referred to as that to which my invention relates, the spindle thereof having applied thereto an attachment constituting one form 70 of the aforesaid offset; Fig. 2 shows the said attachment in side elevation and the spindle in dotted outline; Fig. 3 is a longitudinal sectional view through a wound package formed on a spindle in accordance with 75 this invention, and showing the shape of the package as formed; Fig. 4 is a sectional view on the line $x-x$ of Fig. 3; Fig. 5 is a longitudinal sectional view of the package, showing the shape it is made to assume for 80 use; Fig. 6 is a sectional view on the line $y-y$ of Fig. 5; and, Fig. 7 shows a modification of my invention, illustrating another form of the offset.

In Fig. 1, in a suitable frame or support 85 a , are shown the spindle member b and the thread-guide member generally indicated by c and including the thread-guide proper d and the rotary wheel carrying shaft e , the wheel whereof is indicated by e' , the 90 thread-guide proper d and the shaft e having a suitable coupling means f . In this particular form of winding mechanism, the spindle member rotates (on its own axis), g being a suitable clutch 95 member for rotating it; and the thread-guide member reciprocates, and is susceptible of progressively shifting, parallel with the axis of the spindle, the reciprocating being effected by an oscillating fork h engaging 100 threading on the shaft e and the shifting being accomplished by the wheel e' impinging from time to time against the wound package and so turning shaft e in the fork, all with the effect in the regular operation 105 of the mechanism of progressively advancing the thread-guide member parallel with the spindle while it is reciprocating through a distance representing but a part of the length of the package being formed. 110

In accordance with my invention, as shown in Fig. 1 and 2, I apply to the spin-

dle member *b* an attachment including a collar *i*, adapted to be slipped over the spindle and bear against its shoulder *j* and having a set-screw *k* to removably secure it in place, and, projecting forwardly from said collar, an elongated rib *l* which lies flat against one side of the spindle and has its outer or acting face *m* converging forwardly toward the spindle axis. Preferably, the spindle is cut away somewhat on the side thereof opposite to the rib *l*, as indicated at *n* in Fig. 2; this, however, is not indispensable.

When a cop tube *A* is now slipped on the spindle, its butt-end is caused, by inclined surface *m* of the offset afforded by said attachment, to be displaced or offset laterally with respect to the spindle axis, in the particular adaptation being referred to being incidentally stretched into substantially ovoid shape in cross-section as shown in Figs. 3 and 4.

On the mechanism being now set in operation, on the first reciprocating thrust of the thread-guide member to the right in Fig. 1 its wheel *e'* will impinge against the laterally offset or "high" part of the cop-tube-butt, receiving a rotary impulse that will advance said thread-guide member to the left relatively to the fork *h*. In the ensuing reciprocations of the thread-guide member a layer or layers of windings of thread or yarn will be wound around the butt portion of the cop-tube. Eventually on one of the reciprocations of the thread-guide member to the right the wheel *e'* will impinge against the windings where maintained relatively offset by the offset portion of the cop-tube, receiving another rotary impulse that will again cause the advancement of the thread-guide member to the left; and so on, the windings being progressively advanced along the butt portion of the spindle and so building up into the desired conical heel or butt of the wound package.

The package will have, when completed, approximately the form shown in Figs. 3 and 4 in which, in any cross-section through the portion thereof where the offset affected the windings, the package appears ovoid in contour, this shape being most pronounced at the extreme end of the cop butt and gradually approaching the circular toward the cross section where the tapering heel merges into the cylindrical body. But the heel of the cop may be readily made to assume the form of a perfect cone as soon as the package is slipped on a spindle (compare Figs. 5 and 6) and the bore of the package is thereby straightened out.

The offset may be produced in other ways, for instance, as shown in Fig. 7, where the spindle *b'* has an angular portion *b''* which, as to its cop-tube-butt receiving part *b'''*,

is formed to converge forwardly from a point eccentric of the spindle axis toward the latter. In this case the butt-end of the tube becomes bodily bent, when the tube is forced on the spindle, out of alinement with the axis thereof.

Having thus fully described my invention, what I claim as new and desire to secure by Letters Patent is:

1. Means for forming a wound package including, with the frame, an axial supporting member for the package and a package-engaging thread-guide member, one of said members being rotary around the axis of the supporting member and one reciprocatory longitudinally of said axis to bring the thread-guide member against the wound portion of the package and one of said members being also shiftable relatively to the other longitudinally of said axis to shift the point of winding along said axis, said supporting member having in the portion thereof around which the package-butt-windings are coiled a lateral offset coöperative with the thread-guide member.

2. Means for forming a wound package including, with the frame, an axial supporting member for the package and a package-engaging thread-guide member, one of said members being rotary around the axis of the supporting member and one reciprocatory longitudinally of said axis to bring the thread-guide member against the wound portion of the package and one of said members being also shiftable relatively to the other longitudinally of said axis to shift the point of winding along said axis, said supporting member having in the portion thereof around which the package-butt-windings are coiled a lateral offset coöperative with the thread-guide member and converging forwardly toward said axis.

3. Means for forming a wound package on a cop-tube including, with the frame, a cop-tube-receiving spindle member and a package-engaging thread-guide member, one of said members being rotary around the axis of the spindle member and one reciprocatory longitudinally of said axis to bring the thread-guide member against the wound portion of the package and one of said members being also shiftable relatively to the other longitudinally of said axis to shift the point of winding along said axis, said spindle member having in the portion thereof receiving the tube-butt means for maintaining a part of the tube-butt laterally offset and in coöperative relation to the thread-guide member.

4. Means for forming a wound package on a cop-tube including, with the frame, a cop-tube-receiving spindle member and a package engaging thread-guide member, one of said members being rotary around the

axis of the spindle member and one reciprocatingly longitudinally of said axis to bring the thread-guide member against the wound portion of the package and one of said members being also shiftable relatively to the other longitudinally of said axis to shift the point of winding along said axis, said spindle member having in the portion thereof receiving the tube-butt means for 5 placing a part of the tube-butt into laterally offset relation to the tube, and coöperative relation to the thread-guide member.

5. Means for forming a wound package including, with the frame, an axial supporting member for the package and a package-engaging thread-guide member, one of said members being rotary around the axis of the supporting member and one reciprocatingly longitudinally of said axis to bring the 10 thread-guide member against the wound portion of the package and one of said members being also shiftable relatively to the other longitudinally of said axis to shift the point of winding along said axis, said supporting member having in the portion thereof around which the package-butt- 15

20

25

windings are coiled a longitudinal rib co-operative with the thread-guide member. 30

6. Means for forming a wound package including, with the frame, an axial supporting member for the package and a package-engaging thread-guide member, one of said members being rotary around the axis of the supporting member and one reciprocatingly longitudinally of said axis to bring the thread-guide member against the wound portion of the package and one of said 35 members being also shiftable relatively to the other longitudinally of said axis to shift the point of winding along said axis, said supporting member having in the portion thereof around which the package-butt- 40

45

windings are coiled a longitudinal tapered rib co-operative with the thread-guide member.

In testimony whereof I affix my signature in presence of two witnesses.

EMORY J. LIPPS.
